UNITED STATES PATENT OFFICE.

JAMES GRANT DELANEY AND ASHER LAMBERT, OF NEWARK, NEW JERSEY.

FALL-ROPE CARRIER.

No. 867,578.

Specification of Letters Patent.

Patented Oct. 8, 1907.

Application filed March 18, 1904. Serial No. 198,768.

To all whom it may concern:

Be it known that we, JAMES GRANT DELANEY and ASHER LAMBERT, both citizens of the United States, and residents of Newark, in the county of Essex and 5 State of New Jersey, have invented a new and improved Fall-Rope Carrier, of which the following is a full, clear, and exact description.

Applications filed March 20, 1906, Serial No. 306970, issued August 28, 1906, as Patent No. 829911, and application filed March 22, 1906, Serial No. 307311, issued January 1, 1907, as Patent No. 840443, are divisions of this application.

This invention relates to conveyers or cable ways for hoisting and conveying.

15 The object of this invention is to provide a rope carrier which is simpler and less liable to derangement than any heretofore known or used.

In conveyers of this character it is desirable and necessary to support some or all of the flexible ropes 20 employed from the main cable or trackway so as to prevent sagging and interruption to the successful movement of the carrier, and so as to permit the raising and lowering of the load or bucket from the load carriage at any point between the terminal stations. Each carrier

25 is automatically movable at a predetermined and characteristic relative rate so as to maintain the proper space or distance between successive carriers. To attain this object each carrier is provided with a single propelling element, like a grooved wheel, or pulley; this wheel or

30 element preferably engages the under side of the main track or cable and the upper side of the endless haul rope; the track, the wheel and the haul rope, are in one and the same vertical plane and the resultant thrust of the haul rope forces the single wheel into engagement with the main track. This steadies the carrier and prevents wobbling. With a grooved wheel of given diameter the rate of advance movement is one-half the speed of the haul rope; to secure an increased speed of movement the single wheel is provided with

35 two peripheral contacts at different radial points. The haul rope of smaller diameter than the main track or cable engages the wheel at the shorter radial distance and the main cable engages the wheel at the greater radial distance. To provide these two peripheral contacts a deeper groove bisects the circumferential groove and in this deeper groove, the haul rope, of less diameter, engages the peripheral contact at the shorter radial distance.

This improvement also provides means to insure an 50 effective yielding engagement of the propelling wheel of the carrier between the haul rope and the main cable, thus increasing the certainty of action and avoiding destructive strain on the cable and sheaves.

Reference is to be had to the accompanying drawings forming a part of this specification in which simi-

lar characters of reference indicate corresponding parts in all the figures.

Figure 1 is a side view of the propelling wheel and Fig. 2 is an end view thereof.

There is a main track or cable 12; the haul rope or 60 traverse rope is shown at 14. The fall rope 16 supplies means for raising and lowering the load.

The rope carrier is constructed with a frame 19, which may be of any suitable material—preferably consisting of iron cheek plates between which pass the 65 cable 12, and the lowerrun of the haul rope 14, the cheek plates of the frame 19 are secured by angle pieces 29 held in position by suitable bolts. In the lower part of the rope carrier is a sheave or guide 20 for the fall rope 16, and mounted in the upper part are two carrier 70 wheels 21, 21, that run on the main cable 12 to support the rope carrier. The haul rope 14 runs over two sheaves 22, 22, mounted in the frame and suitably spaced with respect to each other.

The broad wheel base due to the location of the 75 sheaves 21, 21, in vertical planes separated a distance about equal to a diameter of the driving element 23, causes the barrier to maintain a vertical position; this is rendered still more stable by the similar location of the sheaves 22, 22. The position of the rotary driving 80 element 23 with respect to the two pairs of sheaves 21 and 22 is such that the track cable 12 is pinched between the sheaves 21 and the driving element. This all contributes to the stability of vertical position.

The form and disposition of the parts 12, 14, 20, 21, 85 22 and 23, are so regulated that both cables bear tightly against roller 23, the haul rope being sprung or bowed slightly at the opposite sides of the traction roller. This causes the actuating rope (in this instance the haul rope), to press the traction roller upward against the 90 main cable and thus maintain a firm yet elastic engagement between the parts 12 and 23, and 14 and 23. In effect the roller or wheel 23 is gripped between the two cables.

With this apparatus, as the haul rope moves at a certain rate of speed, it imparts a rotary movement to the traction roller or driving member 23, causing the roller to run along the stationary main cable 12 while the rope carrier is advanced at a lower speed than that of the haul rope 14.

By varying the relative distances of the ropes 12 and 14 from the center of the traction roller 23, that is, by providing peripheral contact points or faces at respectively different radial points, the speed at which the rope carrier is propelled with respect to the movement 105 of the haul rope 14 may be varied at pleasure. The drawings show an arrangement by which the rope carrier is made to run at three-quarters the speed of the haul rope. This is done by providing a single traction wheel or roller 23, having two peripheral contact 110

points or faces 26 and 27, at different radial distances; the peripheral contact or face 26 being on the shorter radius and the peripheral contact or face 27 being on the greater radius. The haul rope 14 engages the shorter 5 radial periphery 26 while the main cable 12 engages the longer radial periphery 27. Holes or openings 28 for the adjustment of the sheaves 22 are shown in rows one above another.

In the construction shown the shorter radial periphery 26 is between two annular flanges extending beyond the periphery 26 to form the greater radial periphery 27. The haul rope 14 being smaller than the main cable runs between these flange-like portions and bears on the periphery 26 while the main cable 12 runs upon 15 the outer edges of said flanges.

In connection with the invention described it is pointed out that the employment of a single propelling wheel 23 provides for maintaining the elements 12, 14, and 23, in the same vertical plane and accurately balancing the rope carrier thereon, thus avoiding the side lash or wabbling of the carriage, since the pressure between the parts is in the same plane and central of the carrier.

Having thus described our invention, we claim as new 25 and desire to secure by Letters Patent:

1. In a conveyer, a rope carrier having a frame, a traction roller carried thereby and comprising a small face and flange-like portions at each side thereof, projecting beyond the same and spaced from each other to form a large face, 30 said faces being adapted respectively to engage the haul rope and main cable.

2. A rope carrier for conveyer systems including a driving roller having two faces adapted respectively to be engaged by the conveyer trackway or main cable and the con-

veyer haul rope, said faces of the roller having their central or middle planes coincident, for the purpose specified. 35

3. A rope carrier for conveyer systems having a driving roller with two faces of different diameters adapted respectively to be engaged by the conveyer trackway or main cable and a haul rope, said faces of the roller having 40 their central or middle planes coincident, for the purpose specified.

4. In a conveyer system a track rope and a haul rope combined with a rope carrier including a suitable frame with a single traction roller having separate grooves for 45 the track rope and the haul rope, said roller engaging the under side of said track rope, a pair of anti-friction devices running on said track rope and means for holding the haul rope in driving engagement with the under side of said traction roller.

5. In a conveyer a rope carrier consisting of a single traction roller, a groove or face on said roller for the track rope, a groove or face on said roller for the haul rope, a suitable frame supporting said roller, and a pair of anti-friction devices traveling on the track and means for holding the haul rope in propelling engagement with the under side of said traction roller. 50

6. In a conveyer system two ropes of respectively different diameter combined with a rope carrier consisting of a frame, a single traction roller supported in said frame, 60 two grooves on said roller, having their central planes coincident, corresponding in diameter respectively to the diameter of the two ropes aforesaid, means for pressing said roller against the under side of one rope and means for pressing said roller against the upper side of the other 65 rope.

In testimony whereof we have signed our names to this specification in the presence of two subscribing witnesses,

JAMES GRANT DELANEY.
ASHER LAMBERT.
